UNITED STATES PATENT OFFICE.

ALBERT N. LYBERGER, OF ELYRIA, OHIO, ASSIGNOR OF ONE-HALF TO HARVEY E. WOOD, OF CHESTER, PENNSYLVANIA.

CAR-REPLACER.

1,294,926.

Specification of Letters Patent. Patented Feb. 18, 1919.

Application filed June 24, 1918. Serial No. 241,524.

To all whom it may concern:

Be it known that I, ALBERT N. LYBERGER, a citizen of the United States, residing at Elyria, in the county of Lorain and State 5 of Ohio, have invented a new and useful Car-Replacer, of which the following is a specification.

This invention relates to car replacers.

The object is to provide portable devices 10 for replacing cars upon railroad tracks which may be readily secured in position with relation to the track and the derailed wheels, so that when a pull is exerted upon the car, it will be shifted in a sidewise manner, the wheels being sufficiently elevated to mount upon the rails and assume their proper position thereon, with the flanges of the wheels upon the inner sides of their respective rails.

Another object is to provide a pair of such devices, one for each rail, which may be easily handled and positioned at any point 15 along the track, one of the devices being adapted to be located between the rails and adjacent to one rail for replacing the wheel or wheels situated at such point, while the other device is adapted to be located adjacent to the other rail and upon the outside thereof for like action upon the other wheel 20 or wheels.

A further object is to provide such a pair of devices which may be readily formed by a single casting, which is reinforced so as to withstand the tremendous strain to 25 which such devices are subjected in supporting the great weight put upon them while they are in action.

A full and complete understanding of the invention may be obtained from a consideration 30 of the following detailed description, taken in connection with the accompanying drawing forming a part of this specification; it being understood that while the drawing shows a practical form of the invention, the latter is not confined to strict conformity therewith, but may be changed or modified, so long as such changes or modifications mark no material departure from the salient features of the invention, as specifically pointed out in the appended claims.

In the drawings, in which like reference characters designate corresponding parts throughout the several figures:—

Figure 1 is a plan view of a portion of a

railroad track and showing a pair of the 55 devices of the present invention in position thereon for replacing the wheels of a derailed car, an alternate position of the devices being illustrated in dotted lines.

Fig. 2 is an end elevation of the same, 60 the rails being in cross section and a pair of wheels mounted upon the same, the alternate position of the devices being indicated in dotted lines.

Fig. 3 is an enlarged sectional view 65 through one of the devices, illustrating the manner of its attachment to the rail, at the inner side thereof, and showing a position of the wheel about to be replaced upon the track.

Fig. 4 is a similar view of the other or outside member of the replacing devices and illustrating the corresponding position of the other wheel of the pair.

Fig. 5 is a side elevation of one of the 75 devices showing its position upon the ties of the railroad track and its relation to the adjacent rail.

Fig. 6 is a bottom plan view of the same.

Figs. 7 and 8 are cross sections taken on 80 the lines 7—7 and 8—8 of Fig. 5.

The car replacing means of the present invention consists of a pair of devices constructed precisely alike in the main features, a difference existing, however, in the relative heights of the two members, and their relation to their adjacent rails with which they are adapted to coact, during the operation of lifting and side shifting the wheels to locate them upon the said rails. 85

The wheels of a derailed car generally lie one between the rails and adjacent to the inner side of one of the same, while the other wheel is located in a corresponding position with relation to the outer side of the other 95 rail. The object is to provide devices, which may be secured to the rails in position to receive the wheels at a low point and resting firmly upon the ties, to take the weight and, when the wheels are pulled toward the devices, as when an engine is hitched to the derailed car, to lift the wheels and guide them toward their proper rail and seat them thereon.

To this end, the replacer comprises an 105 inner and an outer member 1 and 2 respectively, each composed of a single casting of suitable metal and preferably formed hollow

to reduce the weight thereof and provided with strengthening webs at certain points.

Each member 1 and 2 comprises an elongated body portion having a gradually upwardly inclined upper surface or platform 3-3 extending from each end thereof to the transverse central point of the same, the two inclined surfaces meeting at the apex 4, constituting the highest point of the surfaces or platforms 3, which surfaces or platforms form a track upon which the flanges 5-5 of the wheels 6-6 are adapted to roll during the operation of replacing the car.

The ends of each of the devices are considerably wider than the central portion thereof, and the width decreases from each end toward the center, as clearly shown in Figs. 1 and 6 of the drawings. In other words, the width of the platform or track surfaces decreases and the upward inclination increases from each end toward the apex 4. An upstanding rib or flange 7 extends from that corner of the two ends remote from the adjacent rail, up and along the inclined platforms or track surfaces 3-3, forming the outer wall thereof, in a direction toward said rails and partaking of the upward inclination of said platforms until they reach the apex 4, where they merge into a longitudinally disposed horizontal portion 8 located adjacent to the rail, and rounded upon the face next to said rail, as indicated at 9.

The sectional views, Figs. 7 and 8, show that the inner walls of the flanges are straight near the ends of the members and incline inwardly as the apex is reached.

Each of the members 1 and 2 is provided with a lateral offset extension 10 arranged longitudinally along the entire side of the device next to the rail, and adapted to fit beneath the head of the rail 11 and abut against the vertical web thereof, as clearly illustrated in Figs. 3 and 4 of the drawings. The said extensions 10 are considerably less in height than the height of the web of the heaviest rail, and those illustrated in the drawings may be taken as indicative of such rails, say what is known as 100 pound rails, a space being thus formed at 12, above the extension 10, into which the head of a lighter rail, such as an 80 or a 90 pound rail might fit as well. The space 13 below said extension 10, is adapted to provide ample space for the accommodation of the heads of the spikes 14 located at the adjacent edge of the base of the rail for holding the same in position upon the ties 15.

Each member 1 and 2 is formed of a hollow shell having inner longitudinal walls 16 including the extensions 10 and an outer longitudinal upright wall 17 adapted to rest upon the ties 15 in spaced relation to the adjacent rail, each of the walls 16 and 17 being provided with downwardly projecting

spurs 17^a for penetrating the ties and preventing any longitudinal movement of the device when once placed in position.

In order to prevent any sidewise movement of the device in a direction away from the rail, each is provided with a clip 18 composed of a flat stout strip of bar metal, angularly bent at an intermediate point, as indicated at 19, and adapted to pass beneath the base of the rail and between the ties and engage the edge of the said base opposite to the member 1 or 2, as the case may be, an upturned hook 20 being provided at the terminal of each clip and adapted to fit over said edge for maintaining such engagement.

Each of the outer longitudinal walls 17 is provided with a slot 21 at a central point of the length of the member and at an elevation substantially opposite the point of contact of the extension 10 with the web of the rail, said slot 21 being adapted to be traversed by the upper longitudinal portion 22 of the clip 18, said portion 22 being provided with a slot 23 for the reception of a wedge 24 which is driven downwardly through said slot 23 to exert a pull upon the clip 18 for the purpose of binding the member 1 or 2 to the rail, the slot 23 being of sufficient length to permit of such binding action, as will be seen by referring to Fig. 3. The fastening device may be varied in construction as the circumstances warrant.

The apex 4 of the inner member 1 is located below the top or tread of the adjacent rail 11 and inclines downwardly from the rib or flange 7 thereof to a point intermediate of the side of the head of the rail, the said flange 7 rising somewhat above the tread of the same. Depending from the inner end of the apex is a substantially vertical wall 4^a which bears against the side of the head of the rail. A space is thus provided between the rail and the flange 7 of the member for the flange 5 of the wheel 6, which, being the one that has previously rested upon the ties between the rails, must be replaced upon its rail with the flange 5 between the rail and the member 1. The said space for the wheel flange and the inclined wall 8 of the apex enables the wheel to be laterally deflected toward the rail as it gravitates along the inclined apex 4, after the wheel has been pulled up the gradually inclined upper surface or platform.

The apex 4 of the other or outer member 2 is also inclined from the flange 7 toward the rail, as seen in Fig. 4, but in this instance is elevated above the rail, the lower portion of the inclined apex coinciding with the adjacent corner of the ball of the rail which, as has been stated, may represent the heaviest rail. The inclination of the apex of the inner member is steeper than the inclination of the apex of the outer member. A vertical wall 4^a is provided at the inner end

of the apex to bear against the head of the rail. The wheel flange will ride up the inclined surface or platform 3 and be gradually moved laterally toward the rail as is 5 the opposite wheel by reason of contact with the respective flanges 7-7, and when the first-named or inner wheel is deflected or skidded in the manner described, the second-named or outer wheel is dragged therewith 10 and caused to cross its rail, when the flange 5 thereof will drop in proper position at the inner side of the ball of the rail, there being nothing to hinder such passage of the same. The operation is very clearly shown in Figs. 15 3 and 4 of the drawings, which represent respectively the inner and outer rails, wheels and replacers. It will be seen that, in the event of a lighter rail being used, the wheel flanges may as readily assume their proper 20 relation to their respective rails.

Transversely disposed strengthening ribs or webs 24 connect the walls 16 and 17 at opposite sides of the clips 18, and openings 25 26 are provided in the said wall 17 for convenience in casting.

From the foregoing it will be seen that simple, strong and durable car replacing means have been devised, which may be easily placed in position in front of derailed 30 wheels for elevating and shifting the same into position upon the rails, and which may be reversed and properly located with relation to the rails for receiving the wheel from either direction, the inner and outer members 35 being respectively located in either event.

What is claimed is—

1. In a car replacer, a pair of members 40 adapted to be placed alongside the inner and outer rails of a track, each member comprising an elongated body portion having a gradually upwardly inclined track surface extending from each end to a central point of the same, the two inclined surfaces meeting 45 ing to form an apex, said surface decreasing in width from each end to said apex, and an upstanding wheel guiding flange extending continuously from the outer corners of each end of the body portion along said surface 50 inwardly toward the apex, and attaining its greatest height at said apex, the apex of one member being higher than the tread of its rail and in the other being lower than the tread of its rail, the apices of the two 55 members being inclined downwardly toward the two rails, the inclination of the lower apex being steeper than the inclination of the higher apex.

2. In a car replacer, a pair of members 60 adapted to be placed alongside the inner and outer rails of a railway track, each member comprising an elongated body portion having a gradually upwardly inclined track surface or platform extending from each end to the transverse center thereof, the

two inclined surfaces meeting forming an apex, said surface or platform decreasing in width from each end to the apex, and an upstanding wheel guiding flange extending from the outer corners of each end of the body portion along said platform or surface toward the said apex and joining therat, said flange forming the outer wall of each platform or track surface and partaking of the inclination thereof, one of said 70 members having its apex disposed above the plane of the tread of its rail while the other member has its apex in a plane below the tread of its rail, the apex of both members and the inner wall of the guiding flange inclining downwardly and inwardly toward the rails, and a vertical wall depending from the inner end of each apex and adapted to bear against the inner side of the head of the adjacent rail, each member being hollow 80 and having a pair of spaced inner and outer walls at the bottom, the spacing of said walls causing them to rest upon the ties outside the base flanges of the rails, the inner walls being straight so as to fit close to said 85 flanges.

3. In a car replacer, a pair of members adapted to be placed alongside the inner and outer rails of a railway track, each member comprising an elongated body portion having a gradually upwardly inclined track surface or platform extending from each end to the transverse center thereof, the two inclined surfaces meeting forming an apex, said surface or platform decreasing in width from each end to the apex, and an upstanding wheel guiding flange extending from the outer corners of each end of the body portion along said platform or surface toward the said apex and joining therat, said flange forming the outer wall of each platform or track surface and partaking of the inclination thereof, one of the said members having its apex higher than the tread of its rail and inclined downwardly and inwardly and contacting with the side of the head of the rail on a level with said tread, and the other member having its apex lower than the tread of its rail and inclined downwardly and inwardly and contacting with the tread of the rail at a point below the tread, and a laterally offset extension arranged longitudinally along the inner side of each member and adapted to fit beneath the head of the rail and bear against the web thereof, said extension being of less 100 height than said web.

4. In a car replacer, a pair of members adapted to be placed alongside the inner and outer rails of a railway track, each member comprising an elongated body portion having a gradually upwardly inclined track surface or platform extending from each end to the transverse center thereof, the two inclined surfaces meeting forming an 105 110 115 120 125 130

apex, said surface or platform decreasing in width from each end to the apex, and an upstanding wheel guiding flange extending from the outer corners of each end of the body portion along said platform or surface toward the said apex and joining therat, said flange forming the outer wall of each platform or track surface and partaking of the inclination thereof, one of the said 10 members having its apex higher than the tread of its rail and inclined downwardly and inwardly and contacting with the side

of the head of the rail on a level with said tread, and the other member having its apex lower than the tread of its rail and inclined downwardly and inwardly and contacting with the tread of the rail at a point below the tread. 15

In testimony that I claim the foregoing as my own, I have hereto affixed my signature. 20

ALBERT N. LYBERGER.
